US0D1010695S

(12) **United States Design Patent** (10) **Patent No.:** **US D1,010,695 S**
(45) **Date of Patent:** **** Jan. 9, 2024**

(54) **COMMUNICATION MODULE HOUSING**

(71) Applicant: **Robert Bosch GmbH**, Stuttgart (DE)

(72) Inventor: **Holger Muehlhoff**, Hoesbach (DE)

(73) Assignee: **Robert Bosch GmbH**, Stuttgart (DE)

(**) Term: **15 Years**

(21) Appl. No.: **29/723,272**

(22) Filed: **Feb. 5, 2020**

(30) **Foreign Application Priority Data**

Oct. 22, 2019 (EM) 007078118

(51) **LOC (14) Cl.** **13-03**

(52) **U.S. Cl.**

USPC **D13/162; D15/7**

(57) **CLAIM**

The ornamental design for a communication module housing, as shown and described.

DESCRIPTION

FIG. 1 is a perspective view of a communication module housing showing my new design;

FIG. 2 is a front side elevational view of the communication module housing of FIG. 1;

FIG. 3 is a rear side elevational view of the communication module housing of FIG. 1;

FIG. 4 is a right side elevational view of the communication module housing of FIG. 1;

FIG. 5 is a left side elevational view of the communication module housing of FIG. 1;

FIG. 6 is a top plan view of the communication module housing of FIG. 1; and,

FIG. 7 is a bottom plan view of the communication module housing of FIG. 1.

The broken lines shown in the drawings illustrate portions of the communication module housing that form no part of the claimed design.

1 Claim, 5 Drawing Sheets
